TIME-IMPACT FUSE FOR HAND GRENADES

Howard W. Greer, Daytona Beach, Fla.

Application January 20, 1950, Serial No. 139,751

5 Claims. (Cl. 102—72)

(Granted under Title 35, U. S. Code (1952), sec. 266)

The invention described in the specification and claims may be manufactured and used by or for the Government for governmental purposes without the payment of any royalty thereon.

This invention relates to fuses for hand grenades and more particularly to a time-impact type of hand grenade fuse.

An object of the invention is a hand grenade fuse reliable in action and provided with a selection of either time-delay or impact firing.

Another object of the invention is a hand grenade fuse extremely sensitive to impact.

Another object of the invention is a hand grenade having means whereby the fuse is provided with means permitting the fuse to become armed for impact firing after it has reached a safe distance from the thrower.

The specific nature of the invention as well as other objects and advantages thereof will clearly appear from the following description and drawings in which:

Fig. 1 is a sectional view of the fuse of this invention showing the fuse assembled to a grenade;

Fig. 2 is a view taken along line 2—2 of Fig. 1.

Referring more particularly to the drawings, the bouchon 1 is provided with the usual cap 2 integral with the handle 3 which is normally disengaged from the fuse when the grenade is thrown and releases the firing pin 4 to strike the primer cap 5 as is more fully described in Patent No. 2,412,636, to Frank Short, entitled "Grenade Fuse" issued on December 17, 1946. The bouchon is threaded fixed to the neck of the grenade 6 as at 7. The reference numeral 8 indicates the explosive charge in the cavity of the grenade. The bottom of the bouchon has formed therein a recess 9 having a reduced portion 10. A booster 11 centrally supporting a primer cap 12 is fixed in the recess of said bottom. A spacer ring 13 in the reduced portion spaces a securing collar 14 from the booster. The securing collar 14 comprises two disks of powder indicated by the reference numerals 15 and 16. The disk 15 is provided with a tapered bore 16a which receives the prongs 17 of the firing pin 18. The disk 16 has a hemispherical bore 19 in axial alignment with the tapered bore 16a. A ball 20 is releasably retained in the bore 16 by means of a bar seat 21 integral with the booster. The disk 15 is made of a relatively rapid burning composition, assuring even ignition of the disk 16 which has a lower burning rate. A firing pin 18 is slidably fixed in a bore 18a in the bouchon in alignment with the tapered bore 16a. A helical spring 22, positioned on said firing pin, having one end abutting a shoulder 23 of said firing pin and its opposite end abutting a shoulder 23a formed in the bore 18a maintains the prongs 17 in firm contact with the ball 20 and prevents displacement of the ball until the grenade strikes the target, provided that the fuse is not first otherwise functioned. A bore 24 extending from the primer recess 5a to the reduced portion 10 of the recess 9 contains an instantaneous powder train 25. Another bore 26 parallel to, but spaced from the bore 24 extends from said recess 5a to a perforation 27

in the booster 11 contains a delay powder train 28. The lever 3 is normally maintained inoperative by means of a conventional safety pin 29 positioned in the bouchon and ears 3a of the lever. An arming pin 33 positioned 5 in the bouchon and firing pin 18 is withdrawn prior to throwing the grenade when it is desired to set the fuse for impact functioning. A guide pin 31 fixed in the bouchon and passing through the slot 32 formed in the firing pin, keeps the firing pin in alignment with the booster primer 10 when the firing pin is urged forward, under the influence of spring 22, to strike the booster primer.

To set the fuse for impact functioning the grenade body and lever are held in the hand of the thrower in the usual manner and the safety pin retaining the lever is withdrawn 15 as well as safety pin engaging the firing pin. When the grenade is thrown the lever and grenade disengage and the striker strikes the primer cap fixed in the top of the bouchon. The primer cap ignites both the time delay train and the instantaneous train, the instantaneous train 20 igniting the rapid burning disk of the securing collar 14 which in turn evenly ignites the slower burning disk of the collar which when consumed leaves the ball suspended between the firing pin prongs 17 and the bar 18. On impact the ball is unseated allowing the firing pin spring to urge the firing pin downwardly, striking the primer in the booster which subsequently causes detonation of the grenade. In the event the impact firing mechanism fails to explode the grenade upon an impact, it will be exploded by the time firing mechanism since the delay 25 powder train 28 is always ignited when the striker 4 strikes the primer cap 5. It is thus seen that the time firing mechanism will always explode the grenade a predetermined time after ignition of primer cap 5, thereby assuring explosion of the grenade regardless of functioning 30 of the impact firing mechanism. If it is desired the fuse may be set for the usual time delay functioning by simply not removing the arming pin. In this case the time delay train ignites the booster in the usual manner to cause detonation of the grenade.

40 I claim:

1. In a hollow body forming a hand grenade, a time-impact fuse comprising a bouchon fixed in said body and having a recessed bottom, a first primer received in a recess formed in the upper end of said bouchon, a spring 45 actuated striker pivotally supported on said bouchon and releasable when said grenade is thrown to fire said first primer, a booster received in said recessed bottom and supporting a second primer centrally in the upper surface thereof, a spring loaded firing pin axially slidable in said bouchon in alignment with said second primer, a combustible securing collar received in said recessed bottom and concentric about said firing pin, a spacer ring in said 50 recessed bottom interposed between said booster and said collar, a bar seat integral with said booster and bridging said second primer, a ball releasably spacing said firing pin and said second primer and engaging said bar seat, said ball being releasably supported on said bar seat by said combustible collar, an instantaneous powder train connecting said first primer and said collar, said firing pin 55 maintaining said ball in engagement with said bar seat upon consumption of said collar, said ball being dislodged at impact to release said firing pin for striking engagement with said second primer, and an elongated time delay train in said bouchon connecting said first primer with said booster.

60 2. The time-impact fuse as described in claim 1 wherein a manually retractable arming pin is positioned in said bouchon and in a perforation in said firing pin, said pin being withdrawn when it is desired to cause the fuse to function upon impact.

65 3. The time-impact fuse as described in claim 1 wherein said securing collar comprises two integral disks of

combustible material, the first of said disks having a rapid burning rate to assure even ignition of the second of said disks and having a central perforation receiving the tapered end of the firing pin, the second of said disks having a slower burning rate and provided with a hemispherical bore opened at its top side in alignment with the said perforation and housing said ball; said ball suspended entirely by said firing pin and said bar seat upon combustion of said collar.

4. In a combination time and impact fuze; a hollow body containing an explosive charge, a booster in said body in detonating relation with said charge, firing pin means in said body axially movable from a first locked position to a second position to detonate said booster, a ball comprising impact dislodgeable means normally maintaining said firing pin in locked position; a primer in said body, a first powder train comprising an axially elongated instantaneous powder charge, a slow burning charge received in a recess concentric about the lower end of said firing pin and in axially spaced overlying relation with said booster, said instantaneous powder charge lying in contiguous relation with said primer on

one end and said slow-burning charge on its other end, there being a semi-spherical cavity formed axially in the lower face of said slow-burning charge receiving said ball, said ball having its upper surface engaging the lower end of said firing pin, and means within said cavity supporting said ball out of contact with said booster to immobilize said pin, said ball being dislodged on impact after consumption of said slow-burning charge, to release said firing pin for movement into said booster to detonate the same.

5. The combination fuze of claim 4, and a second delay powder train comprising an axially elongated powder charge extending between said primer and said booster and transversely spaced from said instantaneous powder charge.
